UNITED STATES PATENT OFFICE.

WILLIAM ALBERT WHITE, OF NEW YORK, N. Y.

LIQUID-FUEL FURNACE.

1,203,292.

Specification of Letters Patent. Patented Oct. 31, 1916.

Application filed April 13, 1916. Serial No. 90,816.

To all whom it may concern:

Be it known that I, WILLIAM A. WHITE, a citizen of the United States, and resident of the borough of Manhattan, in the city, county, and State of New York, have invented certain new and useful Improvements in Liquid-Fuel Furnaces, of which the following is a specification.

This invention relates to a system of liquid fuel burning in furnaces, wherein regulated quantities of liquid fuel are to be atomized in conjunction with suitable proportions of air, within the furnace, the air being initially pre-heated within the furnace front, which is hollow, and said heated air entering the furnace interior, about a centrally disposed burner, in a spiral flow.

Having in mind a system of the above noted character, my present improvements are directed particularly to a novel construction, arrangement, and combination of furnace front elements, as for example in a furnace of the Howden draft type; my said improvements being applicable both under conditions of natural draft, and, with slight modifications, under forced draft.

With these and other objects in view my invention comprises a furnace front composed of two vertical plates, spaced apart and having an inclosing, annular wall, to form an air heating chamber, the rear plate fitting in the furnace end, and carrying a constricted air inner tube, and the forward plate carrying a burner, which extends across the heating chamber and terminates within said constricted tube.

The plate which fits to the furnace end may be in the nature of a frame, having removably fitted thereto several furnace closure members, which serve to receive the impingement thereon of air entering the hollow front, in its transit to the inlet tube; and the surface of each of said plates may bear curvilinear ribs, which tend to impart a spiral direction to the passing air, so that this air may approach and traverse the inlet in a swirling formation.

The forward or outer plate of the furnace front is provided with an upper door and a lower door, both of which are open for the passage of air, through the hollow front, and into the furnace, when operating under natural draft; but said doors being closed under conditions of forced draft, when air of combustion is admitted in the manner usual with the Howden draft type of furnace.

The upper door aforesaid is hinged to a removable cover plate, which carries the burner, said burner having a deflector adjustable thereon, and also having a cone valve 60 slidable thereover, to regulate the air supply. A Venturi, or constricted air inlet tube, is supported by the inner wall of the hollow front, and is arranged to receive, concentrically, the end of the burner tube 65 and the deflector carried by said tube.

My said improved furnace front parts are devised and arranged to be fitted easily and quickly to a Howden draft furnace, to transform the latter from a coal burning furnace into a highly efficient oil burning furnace, with which either natural or forced draft can be employed.

Other features and advantages of my said invention will hereinafter appear.

In the drawings: Figure 1 is a front view, partly in section, of my improved furnace front. Fig. 2 is a vertical section, on the line 2—2 of Fig. 1, and Fig. 3 is a rear end view on the line 3—3 of Fig. 2.

The furnace 1 is provided with an end plate or frame 2, which forms a partial closure therefor, and which supports other elements of the hollow front. Secured to said frame 2, as by bolting thereto, are the members 3, 4 and 5, which together comprise a wall separating the furnace interior from the hollow front. The member 3 is an angular plate, reinforced with a flange 3^a, which lies across the major, rearward, lower portion of the front, the flange being on the inner or furance side of said plate; and the member 4, having a similar flange 4^a, is secured to member 3, by means of bolts connecting adjacent flanges 3^a 4^a, said member 4 completing a partial closure between the hollow front and the furnace, at the lower portion thereof. The conterminous edges of the members 3 and 4, together with the furnace base, surround a lower space which is 90 covered by a heating plate 6, that is adapted to be removably fitted thereto, as by latches 7, pivoted on said plate 6, and finding lodgment in socket pieces 8 on the members 3 and 4. The plate 6, on its surface presented 100 to the interior of the hollow front, is provided with a series of curvilinear ribs 6^a, whose inclination is eccentric relatively to the longitudinal axis of the furnace, for a purpose to be described hereinafter.

The members 3 and 4 support, on the top edges 9, 10, the upper member or plate 5,

2

and said members 3 and 4, have on their top edges, ledges 3^b, 4^b, the better to locate plate 5 thereon; the plate 5 further being bolted to frame 2. Plate 5 is provided, on its surface presented toward the interior of the furnace front, with a flange 11, and with a series of curvilinear ribs 5^a, whose inclination is inward and eccentric relatively to the longitudinal axis of the furnace front, 5 to co-act with the ribs 6^a, in imparting circular direction to entering air impinging thereagainst. A seat describing part of a circle is formed in the upper edge of the member 3, to receive and support an air inlet tube 12, whose upper portion is embraced by the member 5, whose lower edge describes the remainder of a circle, to thus coördinate said members 3 and 5 in providing an annular inclosing seat for said tube. The tube 12, 10 which is constricted centrally, and outwardly flaring at both ends, has a radial flange 13, which abuts against the members 3 and 5, said flange being provided with extending lugs 14, having bolt holes by which 15 it may be bolted to said members. Thus said tube 12, which is of Venturi character, comprises the passage or inlet whereby air of combustion enters the furnace from the hollow front.

20 The outer end of the hollow front is inclosed by an upper cover plate 15, and a lower door 16, the latter being mounted on hinges 17, so that it may swing upwardly and outwardly in opening. Also, in the 25 upper portion of the cover plate 15 I provide a door 18, hinged at 18^a, and adapted to swing downwardly in opening, said door being held closed by latches 19.

30 The cover plate 15 carries, on its inner surface, a tubular jacket 20, adapted to receive and contain a fuel burner (not shown), the support for said jacket having a bushing 21, which centers the burner within the jacket, leaving an annular clearance between said jacket and burner, and said jacket has air inlets 22, in order that a hollow column of air may issue about the fuel jet. A bell-shaped deflector 23 is slidably adjustable over jacket 20, said deflector, with the burner 35 jacket, lying centrally within the inlet tube 12. The deflector 23 is rendered adjustable by means of a rod 24, having handle 25. Also slidably adjustable upon jacket 20, is a conoidal valve 26, to regulate the quantity of air admitted to inlet tube 12.

40 The regular Howden draft intake ports 27 appear in the upper part of the front, regulated by slide valve 28, having hand control 29, and communicating, through passage 30, with the front interior, leaving passage 30 and entering the interior of the front by ports 31; and the air checks 32 are employed, to, when open, permit the passage of air to the lower portion of the hollow 45 front.

When the furnace is to be operated under natural draft, the ports 27 and checks 32 are closed, and the doors 16 and 18 are opened; but when forced draft is to be used, then the doors 16 and 18 are closed, and the ports 70 27 and checks 32 are opened. Thus the conversion from one form to the other is very simply and quickly accomplished.

By means of the construction and arrangement of parts disclosed, air entering the hollow front, for pre-heating therein, is caused to impinge upon the plates 5 and 6, and to be given, by the tangential ribs on said plates, a rotary or swirling direction in its motion toward the air inlet tube 12, which 75 motion, accentuated in speed by the constricted character of said tube, thereby causes a gyratory dispersal of the entering air in the furnace. Further, by partial entrainment of the entering air over the edge 80 of the bell-shaped deflector, and the issuance of liquid fuel from the burner, with the fuel enveloping air from the burner jacket, an atomizing and mixing condition is set up between the fuel and air, 85 whereby flame propagation with highly efficient combustion begins close to the burner and is effective through the full length of the furnace.

Variations may be resorted to within the 90 spirit and scope of my said invention, and parts thereof used without others.

I claim:

1. The combination, in a liquid fuel furnace, of a hollow front for said furnace, the inner wall of said front consisting of a number of plates, the plates at the lower part of said wall having flanges by which they are bolted together, and having alined seating flanges, an upper plate seated upon said alined flanges, said upper and lower plates having a central clearance, and an air supply tube fitting and supported within said clearance, said tube having a circumferential flange to lie against said plates, and fastening means between said flange and plates. 105

2. The combination, in a liquid fuel furnace, of a hollow front for said furnace, the inner portion of said front consisting of a frame, with a number of air impingement plates fitted to said frame, and an air inlet tube extending through said plates, said plates bearing a series of ribs which extend part-way only through the depth of said hollow front, and said ribs being inwardly and eccentrically arranged with relation to said inlet tube, to direct air in swirling form thereto. 110

3. The combination, in a furnace of the Howden draft type, having a hollow front, 120 of a constricted air inlet tube, penetrating the inner wall of the furnace front, a burner axially penetrating said front and lying within said inlet tube, a deflector for said burner, and a conoidal valve to regulate the 125

inlet, said inner wall having ribs extending part-way only through the depth of said hollow front, and said ribs being inwardly and eccentrically arranged, relatively to said inlet tube, to direct entering air in swirling form toward said tube.

Signed at the borough of Manhattan in

the city, county and State of New York,
this 11th day of April A. D. 1916.

WM. ALBERT WHITE.

Witnesses:

F. W. BARKER,
EDWARD DURANT.
